UNITED STATES PATENT OFFICE.

ROLAND E. ENGLISH, OF MOUNT RAINIER, MARYLAND.

GAS COMPRESSOR.

Application filed March 10, 1923. Serial No. 624,076.

To all whom it may concern:

Be it known that ROLAND E. ENGLISH, a citizen of the United States, residing at Mount Rainier, in the county of Prince 5 Georges, State of Maryland, has invented certain new and useful Improvements in Gas Compressors, of which the following is a specification.

This invention relates to compressors, and 10 particularly to gas compressors for use in connection with ice producing plants.

An object of the invention is to provide a compressor of such construction as to be capable of employment either as an independent self-contained power source for forcing gas or other fluid through the coils, or it may be used in conjunction with standard plants having compressors or pumps of other types in use; acting in the capacity of 20 an auxiliary compressor.

A further object of the invention is to provide a compressor of such character as to be of small compass and to occupy but a small amount of space, and which is constructed in such manner as to produce a maximum amount of power from the energy expended, and to create in the coils a continuous and uninterrupted flow of gas.

Further objects reside in the construction 30 of a compressor having but few simple and readily assembled parts; which may be constructed at comparatively small expense; which has its several parts so made and assembled as to minimize the opportunity for wear, breakage or derangement; which requires a minimum amount of energy in its proper operation; and which will prove thoroughly practical and efficient in use.

With these and other objects in view, the 40 invention consists of the features of construction, combination and arrangement of parts, hereinafter fully described and claimed, reference being had to the accompanying drawings, in which:—

Figure 1 is a side elevation of a compressor constructed in accordance with the invention,

Figure 2 is a longitudinal section view taken through the improved compressor, the same being on a slightly enlarged scale,

Figure 3 is a transverse sectional view on line 3—3 of Figure 2,

Figure 4 is a similar view on line 4—4 of Figure 2,

Figure 5 is a face view of one of the rotatable valve disks,

Figure 6 is a sectional view taken on line 6—6 of Figure 5,

Figure 7 is a sectional view taken on line 7—7 of Figure 5,

Figure 8 is an edge view of the valve 60 disk,

Figure 9 is a plan view of one of the travelers,

Figure 10 is a longitudinal sectional view taken through a preferred type of traveling 65 block,

Figure 11 is a transverse sectional view taken through the block,

Figure 12 is a longitudinal horizontal sectional view taken through the block, and 70

Figure 13 is a detail fragmentary view showing one means whereby the movable gasket in the discharge chamber may be controlled.

The invention in its preferred embodiment 75 includes a pair of spaced heads 15 and 16 of proper size and weight and being constructed of any preferred material. These heads are spaced apart a proper distance to accommodate between them the mechanism 80 of the pump per se, and may be rigidly secured to a proper base by passing bolts through the outturned feet 17.

The heads 15—16 are connected by a casing indicated generally at 18, this casing 85 preferably being constructed of a number of plates of uniform size and construction to facilitate building up of the casing and properly assembling the pump parts therein.

Each of the heads 15—16 is provided with 90 an annular series of openings or chambers 19 to receive cylinders 20. In the present instance, each head is provided with five of these cylinders, and the cylinders of one head are axially alined with the cylinders 95 of the opposite head. These chambers 19 open at the outer faces of the heads, and snugly receive the cylinders 20.

The cylinders are each equipped with a piston 21, and the pistons of the alined cylinders of the heads 15—16 are connected by rods 22. These rods receive their longitudinal or impelling movements through the instrumentality of a rotor 23 mounted upon a shaft 24 rotatably carried by the heads 100 15—16; the rotor 23 being disposed between the said heads and housed by casing 18. Each of the heads is provided with roller bearings 25 to properly support the shaft 24 and to reduce friction to a minimum. 110

The several plates constituting the casing 18 are each provided with block guides 26, within which the traveling blocks or heads 27 slide. These blocks are rigidly connected 5 to their respective piston rods 22. Each block carries an inwardly projecting pin or stud 28 which rotatably carries a traveler 29; the latter being disposed within the cam groove 30 in the rotor 23. The travelers 29 10 are provided with anti-friction rollers 31 to engage the side walls of cam 30 and to eliminate, as much as possible, friction of the parts during the operation. Furthermore, the traveler for each block has interposed 15 between itself and its supporting pin or stud anti-friction members 32, to further reduce friction of the parts.

The travelers 29 may be of any preferred type or construction, however, in the present 20 instance, they are constructed of superimposed plates as shown, having their ends cut away to receive the anti-friction rollers 31, and these plates are rigidly held together by means of bolts 33. The rollers 31, as 25 will be observed, protrude beyond the sides and ends of the traveler a distance sufficient to ensure against any part of the traveler per se coming in contact with the walls of the cam groove 30.

30 In Figures 10-11-12 there is illustrated a type of traveling block which may be employed in the practical construction of the compressor. This block comprises the body portion 27, having wear plates 35 arranged 35 upon the top and sides thereof so as to contact with the bottom and side walls of the guides 26, and these plates are adjusted by moving the wedge members 36 which are interposed between the plates and block 27. 40 These wedge plates, it will be understood, are controlled in their movements by operation of the lock nuts 37 upon the stems 38 carried by the wedges. By equipping the body 27 with the adjustable plates in this 45 manner, it is apparent that compensation may be made for wear or disalignment that might occur in the said sliding blocks.

The outer face of each head 15 is provided with an annular recess to receive a 50 circular plate 40, which, when positioned in the recess, has its outer face disposed flush with the corresponding face of the head 15. The plate 40 is equipped with a series of circular openings corresponding in position 55 and size with cylinders 20, and the said cylinders are threaded into the said openings of the plate. The outer face of each plate 40 is provided with an annular channel or recess to receive an annulus 41 prefer- 60 ably formed of Babbitt-metal, and the outer face of this annulus is disposed flush with the corresponding faces of plate 40 and head 15. The outer extremities of shaft 24 each have secured rigidly thereto a valve 65 plate or disk 42 which is of such size as to

cover the cylinder openings in the head, plate and annulus. The disk 42, sometimes referred to as the valve disk, is provided with intake and exhaust ports or openings indicated at 43 and 44, respectively; the intake openings adapted to pass over the outer half of each cylinder, and the exhaust ports being so located in the disk as to pass across the inner half of each cylinder opening. The valve disk is also provided at a proper point with a conventional type of safety valve indicated at 45, the purpose and function of which will be hereafter specified. The openings or ports 43-44 have arranged therein vanes 46 disposed at such angle as to impel gases in the proper direction. The vanes 46 of the intake port are disposed in such direction as to tend to gather gases and impel them into the cylinders opened by the said port, while the vanes of the discharge or exhaust port are disposed at such angle as to create a tendency in compressed gas within the underlying cylinder to move outwardly therefrom.

The outer face of each head 15-16 has secured thereto a dome or housing 50 with which communicate pipes 51 to supply gas to the compressor mechanism. The intake ports of the valve disks 42 communicate with the chambers thus formed by the domes 50.

Each of the disks 42 carries a cone member 53, rigidly secured at its inner or larger end to its adjacent valve disk and enclosing the exhaust port 44 and safety valve 45 of said disk. The outer ends of the cone chambers terminate in tubular members 54, which are suitably mounted in bearings carried by the outer portions of domes 50. These bearings, indicated at 55, are hollow, and have communicating therewith the discharge pipes 56, and the chambers formed by these hollowed portions receive gas under pressure from the tubular members 54 through the ports or discharge openings 57 in said tubular members. A packing gland tightly seals the tubular portion 54 in its bearing, and movable plates 58 are arranged in each bearing to maintain the packing in proper compactness. These plates are adjustable longitudinally upon the tubular members 54, and are controlled by operation of lock nuts 59 upon threaded stems 60 swiveled at their inner extremities in said plates. The outer extremities of these stems 60 pass through the removable cover plate 61 for the bearing, and a gland nut 62 seals the cover head upon the bearing against leakage.

In order that a proper tight fitting of the cylinders against their adjacent valve disks 42 may be assured, expansion springs 63 are employed. These expansion springs rest at one end against a rigid part 64 of the head, and bear at their opposite ends against the 130

inner closed ends of the cylinders, and therefore maintain the cylinders at all times at the outer limits of their movements. This construction ensures tight fitting of the Bab-
5 bitt metal gasket against the rotatable disk plate, and prevents leakage as well as compensates for any wear that may occur due to continuous operation of the device.

The tubular member 54 at one end of the
10 compressor comprises a drive shaft, and has secured thereto a belt or drive wheel 68 which may be connected with any source of power, or, this wheel may be coupled with a drive head 69 of any conventional type of
15 electric motor.

One of the plates constituting the casing
18 may be apertured and closed with a hand opening 70, whereby access may be readily had to the interior of the casing for repair
20 or adjustment of any of the parts.

Gas from the brine carrier is supplied to the interior of the domes 50 through pipes 51, the flow of the gas through said pipes being augmented or caused by the partial
25 vacuums created within the domes due to the rapid operation of the pistons within their cylinders. The pipe 51 also has an extension 71 communicating with the interior of the casing 18, whereby any gases present
30 within said casing, due to any leakage that may have occurred, will be withdrawn from said casing and taken into the domes 50 for compression and circulation. The discharge pipes 56 rise from their respective discharge
35 chambers and unite with a common pipe 72 leading to the condensers.

In operation, rotary motion is applied to shaft 54 by any available or desired instrumentality, and this rotary movement is im-
40 parted to the valve disk 42 by means of the cone member 53 rigidly secured thereto. This power, in turn, is imparted to shaft 24, which causes rotor 23 to turn, and also the valve disk at the far end of the compressor
45 and its associated cone member 53. As the rotor 23 turns, the pistons will be caused to reciprocate within their cylinders. The cam groove 30 will determine the proper timing of the movements of the various pistons, as
50 will be readily understood. When a piston has reached the outward limit of its movement and immediately prior to its retracting movement, the valve disk 42 will be in such position as to cause the intake openings or
55 ports therein to begin to overlie the outer end of the cylinder, thus opening the interior of the cylinder to the interior of dome 50. Throughout the retracting or inward travel of the piston this port remains "open"
60 so that gas will be drawn into the cylinder therethrough. This movement of the gas is augmented by the peculiar construction of the vanes as heretofore described. When the piston has reached its extreme inner position
65 and just prior to the start of its outward

travel, the intake port in the valve plate or disk will have moved out of registry with the outer half of the cylinder, closing and tightly sealing the communication between the interior of the cylinder and dome 50,
70 while at the same time the port 44 of the disk will begin to move into registry with the interior of the cylinder. The continued outward travel of the piston causes the gases in front of the same to be forced through the
75 port 44 and into the cone chamber 53, from whence it travels under high pressure through ports 57 in tubular member 54 and into pipes 56. The operations of the pistons and valve disks are then repeated, as will be
80 understood. The pistons and valve disks are so timed that two or more of the cylinders will be drawing gas into their cylinders, while the remainder of the cylinders will be discharging, thus
85 creating a continuous intake and discharge of gases and creating continuous flow in the pipes leading to the condenser. The safety valve 45 is arranged in the disk 42 immediately in advance of discharge port
90 44, and is so positioned that should compression to a dangerous degree arise in the cylinder immediately underlying the same prior to the registry of the discharge port 44 there-
95 with, the valve will open and permit escape of gases before damage can result in the mechanism.

From the foregoing it is apparent that I have provided a compressor which is fully capable of effectively carrying forth the several objects set forth, and which will prove effective in operation and economical in construction, operation and maintenance.

Having thus fully described my invention,
I claim:—

1. In a device of the class described, a casing, a plurality of cylinders arranged in groups in said casing, the cylinders of the said groups being axially aligned, pistons in said cylinders, rods connecting the pistons of the cylinders of one group with those of the other, means for moving said rods, a rotatable member for each of said cylinder groups, each of said members having intake and exhaust ports adapted to be brought at predetermined times into communication with each of said cylinders, and the said rotatable members being operated by the said rod moving means.

2. In a device of the class described, a pair of oppositely disposed heads, each head having a chamber therein, a cylinder in each chamber, the said cylinders being axially aligned, pistons in said cylinders, rods connecting said pistons, means for moving said pistons, the said chambers being deeper than said cylinders, springs normally forcing said cylinders to their limit in one direction, and valves for each cylinder.

3. In a device of the class described, a

- pair of heads arranged in spaced relation, each head having chambers therein alined with the chambers of the opposite head, open ended cylinders in each of said chambers 5 with their open ends disposed outwards, a rotatable valve disk on the outer face of each head, springs for forcing said cylinders against said valve disks, pistons in each cylinder, rods connecting the pistons of the opposite heads, and means for moving said pistons.
4. In a device of the class described, a head having chambers therein, cylinders in said chambers, a gasket connecting all of 15 said cylinders and disposed flush with said head, a rotatable valve disk on said head and bearing against said gasket, and springs forcing said gasket into tight engagement with said disk.
- 20 5. In a device of the class described, a pair of oppositely disposed heads each having a series of chambers therein opening upon the outer faces of said heads, rotatable valve disks on the outer ends of said 25 heads, cylinders in said chambers, a gasket for each head, each gasket interposed between the head and the adjacent disk, springs forcing said cylinders and gasket in an outward direction, pistons in said cylinders, and means for moving said pistons.
- 30 6. In a device of the class described, a casing, oppositely disposed cylinders in said casing, a rotatable valve disk for each series of cylinders, an outlet chamber carried by 35 each disk and in communication with certain of the valves of said disk, a dome enclosing the outer portions of each series of said cylinders and enclosing said chambers, an inlet pipe communicating with each 40 dome, pistons in each cylinder, and means for operating said pistons and rotating said disks.
7. In a device of the class described, a casing, a head at each end of said casing, a 45 dome enclosing the outer side of each head, pump elements in each head, a rotatable valve disk for each head within said domes and having valve openings therein, a cone chamber enclosed by each dome and carried by its respective disk, the interior of each 50 chamber being in communication with certain of said valve openings and the other valve openings of said disks being in communication with the interior of said domes,
- means for rotating said disks, and means for operating said pump elements.
8. In a device of the class described, a head, pump cylinders in said head, pistons in said cylinders, a valve disk rotatably mounted on a face of said head and having 60 openings therein communicating with different portions of said cylinders, a dome covering the outer portion of said head and forming an inlet chamber, an outlet chamber within said dome carried by said disk 65 and in communication with certain of said pistons, and means for operating said pump cylinders and rotating said disk.
9. In a device of the class described, a casing, heads at the ends of said casing, the 70 said casing comprising plates arranged in sections, each head having a series of cylinders therein and the cylinders of one head being axially alined with those of the other head, pistons in said cylinders, rods connecting the pistons of one head with the corresponding pistons of the opposite head, a rotary member in said casing, a shaft journaled in said heads and carrying said rotary member, a cam groove in said rotary member, a slide bearing for each rod, a slide in each bearing connected to its respective rod, a traveler for each of said slides and engaged in said groove, a dome enclosing the 75 outer portion of each head, a cone chamber within each dome, a valve disk for each head carried by said shaft and having spaced openings to communicate alternately with different portions of said cylinders, the said cone chamber connected to its adjacent disk and in constant communication with certain of said openings, and means for rotating said shaft.
10. A bearing for outlet chambers comprising a head, a tubular member rotatably mounted in said head and having openings 80 therein disposed within said head, the interior of said head comprising a chamber, a packing ring within said chamber and enclosing said tubular member, threaded members in said head for moving said ring, a packing gland enclosing the outer portion of said tubular member, and an outlet pipe in communication with said chamber.
- In testimony whereof, he affixes his signature. 105
